UNITED STATES PATENT OFFICE

EDWARD C. HOYER, JR., OF RICHMOND, VIRGINIA, AND FRANK B. LE FEVRE, OF CINCINNATI, OHIO

PORTABLE CABINET AND FOLDABLE STAND THEREFOR

Application filed September 8, 1928. Serial No. 304,708.

This invention relates to portable stands and particularly to a stand and cabinet designed to be supported thereby.

The general object of the present invention is to provide a cabinet with a stand hingedly connected to the cabinet and so formed that it may be folded up entirely within the lower portion of the cabinet.

A further object is to provide a construction of this kind particularly adapted to portable phonograph cabinets, wherein the cabinet is formed with a phonograph compartment and a stand containing compartment into which the stand may be folded, there being a slide closing the bottom of this compartment and holding the folded stand in place.

A further object is to provide a construction of this character in which the stand is formed of a plurality of sections preferably 20 of thin sheet metal adapted to be folded into parallel relation and within the cabinet and in which the sections of the stand may be locked in their unfolded and supporting position.

25 Our invention is illustrated in the accompanying drawings wherein—

Figure 1 is a perspective view of a portable cabinet and foldable stand constructed in accordance with our invention;

30 Fig. 2 is a vertical section of the stand unfolded;

Fig. 3 is a detail elevation of flange 18 showing means for holding the two flanges together; and

35 Fig. 4 is a longitudinal section through the cabinet and the stand, showing the stand folded.

Fig. 5 is a face view of the bolt carrying flange and of the nut, the bolt being in section.

40 Referring to these drawings 10 designates the cabinet which, as before remarked is particularly designed for holding a portable phonograph. This cabinet has the cover 11 and the bottom of the cabinet is formed by a

45 slide 12 operating in grooves so that when the slide is withdrawn, the entire bottom of the cabinet is open. A partition 13 forms the bottom of the phonograph compartment and the top of the compartment wherein the foldable stand may be collapsed and held.

50

Hinged to the side walls of the cabinet 10 adjacent the bottom thereof and below the partition 13 are the two oppositely disposed stand sections 14. Each of these sections is formed of sheet metal and is flanged at its lateral margins as at 15. The sections are cut away as at 16 so as to reduce weight as much as possible without reducing strength. The flanges 15 at their upper end are pivoted at 17 to the side walls of the cabinet at a point above 60 the guides for the slide 12. The lower end of each of the sections 14 extends beyond the flanges 15 and is angularly disposed with relation to the planes of the sections 14 at 18, so that when the sections 14 are swung downward into convergent relation, as illustrated in Fig. 2, these lower flanges 18 will abut against each other. One flange is formed with key-hole slots 19 and the other carries a bolt 20, whereby these flanges may be held together in abutting relation. Any number of these bolts 20 may be used and we do not wish to be limited to the use of these bolts as means for fastening these flanges to each other as other fastening or engaging means may be used.

Disposed below the sections 14 are the sections 21 also preferably made of thin sheet metal and having lateral flanges 22. These lateral flanges at their upper ends are pivoted to the lower end of the flanges 15 at 23, in such manner that the sections 21 may turn up inside of and against the lower face of the sections 14. Knee braces 24, formed in two jointed sections are each pivoted at its upper end to the flanges 15 and at its lower end to the flanges 22. These knee braces break outward at the middle, as shown in Fig. 2, so that they may fold up upon each other when the sections 21 are folded up within the sections 14.

The lowest sections 25 are also formed of thin sheet metal having lateral flanges 26 and these are inserted within the lower ends of the sections 21 and are pivoted at 27 within these sections so that the sections 25 may fold up within and against the under face of the sections 21. When these sections 25 are extended they will be in line with the sections 21 and extend divergently downward, and

the weight of the cabinet will hold them against any inward movement in an obvious manner. When these sections are folded up, however, they will be disposed parallel to and 5 against the end faces of the sections 21, and both the sections 25 and 21 will be folded up within the sections 14. It will be noted from Fig. 2, that the lateral flanges 15 of one of the sections 14 are angularly bent at 28 and 10 the pivots 17 for these sections pass through the extremities of these angularly bent terminals of the flanges 15 of this section. This is to permit one of these sections 14 to be disposed in the upper portion of the stand containing compartment, while the other section 15 is disposed in the lower portion.

As illustrated, one of the flanges 18 is formed with holes for the passage of the bolts 20, the other flange being formed with 20 the key-hole slots 19, as previously stated. The bolts 20 are passed through the round holes in the flange 18 of the left hand plate in Fig. 2 and lock thereto by a thin hexagon nut, the diameter of which is small enough 25 to permit it to fit within the hole of the key-hole slot in the right hand plate 14. The purpose of this key-hole slot is to obviate the necessity of removing the bolt at any time, thus the bolts 20 are rigidly fixed to 30 the flange 18 of the left hand section in Fig. 2 and a thumb screw is loose on the bolt.

While preferably, the sections 14, 21 and 25 will be made of thin sheet metal, yet we do not wish to be limited to this as other thin 35 material might be used.

It will be seen that a stand and cabinet constructed in accordance with our invention can be cheaply made and is very strong and rigid in use and may be folded into a 40 very compact arrangement and enclosed within the phonograph cabinet itself, so that the stand and cabinet may be picked up and carried as one unit, the stand sections being held within the cabinet and in folded condition by the slide 12. When it is desired to 45 use the stand the slide 12 is withdrawn permitting the sections to be unfolded in such manner as to bring the sections 14 into a downwardly convergent position. These 50 sections are then engaged with each other as by means of the bolts 20 or other fastening devices, and then the sections 21 and 25 may be turned down into a downwardly divergent relation and the braces 24 brought to 55 their locking or vertical position.

While we have particularly designed this structure to be used in connection with a portable phonograph cabinet, obviously, we do 60 not wish to be limited to this, as the structure might be used as a portable table or as a portable cabinet for carrying other articles than phonographs. A cabinet constructed in accordance with our invention is very compact and may be readily carried on the run-

ning board of an automobile and is particularly useful for tourists and campers.

While we have used the term cabinet to designate the box-like structure 10 with its cover 11 shown in Fig. 1, this box-like structure being formed with the compartment within which the stand is foldable, we consider the word cabinet to be broad enough to include not only a structure which is closed by the lid, but a box-like structure which is open at its top like a tray but formed with a compartment within which the foldable supporting sections of the stand may be folded.

What we claim is—

1. A cabinet having an open bottom and a closure adapted to close said bottom and a stand comprising two opposed upper sections pivoted to the cabinet and adapted to be folded into parallel relation within said cabinet, and lower sections, each pivoted to the lower end of one of the upper sections, and adapted to be folded within the upper sections, and when unfolded to extend downward in divergent relation, braces for holding the lower sections in the last named relation to the upper sections, and lowermost sections operatively pivoted to the lower ends of the second named sections and adapted to be turned into alinement therewith or into parallel relation therewith.

2. A cabinet having an open bottom and a closure adapted to close said bottom, and a stand comprising two opposed upper sections pivoted to the cabinet and adapted to be folded into parallel relation within said cabinet, and lower sections, each pivoted to the lower end of one of the upper sections, and adapted to be folded within the upper sections, and when unfolded to extend downward in divergent relation, braces for holding the lower sections in the last named relation to the upper sections, lowermost sections pivoted to the lower ends of the second named sections and adapted to be turned into alinement therewith or into parallel relation therewith, each of these sections being formed of thin sheet material flanged at their lateral margins.

3. A structure of the character described comprising a cabinet open at its bottom, a closure adapted to close the bottom of the cabinet, opposed sheet metal stand sections each pivotally connected at its upper end to the side walls of the cabinet and adapted to be folded up within the cabinet in parallel relation or extending downward into convergent relation, each of said sections at its lower margin having an annular flange the flanges abutting when the sections are turned into convergent relation, fastening means detachably holding said flanges abutted, and a plurality of sheet metal sections pivotally connected to each other and to the lower ends of the first named sheet metal sections and foldable into parallel relation to each other.

and the first named sections or into a downwardly divergent relation, and foldable braces for holding the last named sections in their divergent relation.

5 4. A structure of the character described, including a cabinet open at its lower end, a closure adapted to close the lower end of the cabinet, oppositely disposed sheet metal sections, each flanged at its side margins, the
10 sheet metal sections being pivoted through said flanges to the side walls of the cabinet above the path of movement of the slide whereby said sections may be turned into parallel relation to the lower end of the cabinet, means on said sections whereby they may be held in a downwardly convergent position, a pair of sheet metal sections flanged at their lateral margins fitting within the flanges of the first named sections and pivoted thereto for movement to a parallel or angular relation, a third pair of sheet metal sections having lateral flanges fitting within the lower ends of the second named sections and pivoted thereto, whereby they may be
25 turned into parallel or alining relation therewith, and sectional braces connecting the flanges of the first named sections to the flanges of the second named sections.

In testimony whereof we hereunto affix our
30 signatures.
